CONCENTRATOR

Lyle McLean, Portland, Oreg.

Application March 8, 1941, Serial No. 382,439

3 Claims. (Cl. 209—44)

This invention relates generally to the mining industry and particularly to a concentrator.

The main object of this invention is to construct a concentrator whereby precious metals may be efficiently recovered by air flotation.

The second object is to construct a concentrator wherein there will occur a natural flow of materials in which the recovered metals gravitate in one direction while the gangue is moved by air flotation in a different direction toward the end that there will be produced a complete separation of the gangue and metals being recovered.

The third object is to produce a concentrator of the class described especially adapted to the treatment of the finer material due to the fact that all of the gangue is kept in flotation during the concentrating process.

These and other objects are accomplished in the manner set forth in the following specification as illustrated in the accompanying drawings, in which:

Fig. 1 is a vertical section through the device.

Fig. 2 is a transverse section taken along the line 2—2 in Fig. 1.

Fig. 3 is a plan showing the hopper.

Fig. 4 is a plan of the concentrating section showing the concentrating plate with a portion of the screen removed from above same.

Fig. 5 is a section taken along the line 5—5 in Fig. 8.

Fig. 6 is a fragmentary end elevation of the concentrator showing the air lines and dust tubes.

Fig. 7 is a fragmentary section taken along the line 7—7 in Fig. 4.

Fig. 8 is a fragmentary section at a much enlarged scale showing the construction of the perforated concentrating plate, its mounting and the superimposed screen showing a somewhat modified form of construction.

Similar numerals refer to similar parts throughout the several views.

Referring in detail to the drawings, there is shown a perforated plate 10 which in this case is circular in form and is somewhat lower at its innermost portion 11 while its outermost edge 12 is supported by a ring 14. The under side is provided with a groove 15 to receive a packing 16 which engages the upper edge of the conical inner shell 17 whose innermost portion 18 is cylindrical in form.

The end 11 terminates in an internally threaded coupling 19 in which is secured the tubular bleeder pipe 20 which extends downwardly through the center of the innermost portion 18 of the inner shell 17. The shell portion 18 and the bleeder pipe 20 are separated by the spacing collar 21 and the parts secured by means of the set screws 22.

Outside of the member 18 is an intermediate cylindrical portion 23 which is held in concentric relation with the portion 18 by means of the spacing bushing 24. The cylindrical intermediate portion 23 supports the conical intermediate portion 25 on whose upper edge 26 is secured a ring 27 which supports the perforated plate 28 in cascade fashion above the plate 10. The plate 28 also slopes downwardly toward the center of the device and is spaced vertically from the plate 10 by means of a spacing ring 29 whose underside is provided with radial slots 30.

Outside of the portion 23 and spaced therefrom, is a cylindrical outer portion 31 which is spaced from the portion 23 by means of a bushing 32 and secured thereto by means of the screws 33. In the upper end of the member 31 is disposed the conical portion 34 whose upper end 35 has mounted thereon the outermost perforated plate 36 whose lower end rests upon the ring 37 which in turn rests upon the plate 28 and is notched similarly to the ring 29.

Disposed above the plates 10, 28 and 36 is a screen 38 which is supported by the concentric rings 39, 40 and 41 which in turn are united by the radial spokes 42 whose outer ends 43 rest upon the ring 44 which forms a wall around the outside of the outermost screen plate 36. The screen 38 slopes downwardly toward the central ring 39 which is directly above the opening 45 in the coupling 19.

Within the coupling 19 is disposed a head 46 whose perforated top 47 occupies the opening in the ring 39. The radial arms 48 on the head 46 facilitate the rotation of the head and form a support for the ring 39.

The perforated head 46 is connected by means of the airpipe 49 to the pipe 50 which contains the control valve 51. The pipe 50 is connected to the air manifold pipe 52 which is connected by means of the pipe 53 to a suitable air supply (not shown).

The manifold 52 is provided with an outlet pipe 54 including a valve 55 and a connection 56 by means of which air is admitted through the openings 57 to the space 58. That is, it provides a supply of air to the perforated plate 10.

The manifold 52 is also provided with an outlet pipe 59 including a control valve 60 and a connection 61 which admits air through the openings 62 to the space 63 under the plate 28.

The manifold pipe 52 is also provided with an outlet pipe 64 including the control valve 65 and connection 66 to which air is admitted through the hole 67 to the space 68 directly under the plate 36.

It will be noted that the plates 10, 28 and 36 are in cascade relationship and that the grooves 30 permit streams of air to be blown radially across the plates 28 and 10 in an inward direc-

tion thereby insuring against the materials from coming to rest upon the surface of the plates between the openings 69 thereof.

In order to provide a controlled supply of material there is provided a hopper 70 having an inverted conical spreader 71 adjustably mounted on the threaded spindle 72 which is supported by the spokes 73 disposed across the opening 74 of the hopper 70. It is desirable to provide the wings 75 on the spreader 71 to facilitate the rotation thereof and also to provide a clamping nut 76 to hold the spreader 71 in a desired position. A slidably gate 77 is provided under the opening 74 to completely or partially cut off the supply of materials passing out of the hopper 70.

The parts thus far described are held in their desired relationship by means of the upright supporting frame 78 and the diagonal member 79 together with the horizontal tie members 80.

The outlets 81, 82 and 83 are connected by the pipes 84, 85, and 86 to the valves 87, 88, and 89 to which are connected the dust catchers 90, 91, and 92 whose lower ends are preferably closed by the caps 93 in order to remove the dust therefrom.

The operation of this form of the device is as follows:

Assuming that a supply of material 94 is contained within the hopper 70 and this material is permitted to flow downwardly through the opening 74 under the control of the spreader 71 and the gate 77, as the material falls upon the screen 38, air is permitted to flow from the manifold 52 through the perforated plates 10, 28 and 36 in a manner to cause a violent bubbling or boiling action in which the material is made to dance continually upon the screen. The smaller, heavier particles pass through the screen 38 onto the plates 10, 28 and 36 where they continue to be agitated and the heavier metallic particles are worked downwardly by gravity while the lighter gangue is carried upwardly and outwardly by the air current.

As the materials on the plates 10, 28 and 36 are worked toward the central opening and descend into the bleeder pipe 20, they are gradually concentrated and caught in the pipe 20 from which they are withdrawn by removing the cap 95.

It will be noted that the head 46 is perforated on its upper side and air from the pipe 49 keeps the material above the head 46 in constant agitation.

It will be observed that some dust falls through the plates 10, 28 and 36 and falls to the lower end of the respective compartments from whence it is carried into the dust catchers 90, 91 and 92 by inertia since the air coming from the connections 56, 61 and 66 moves this material horizontally and since the catchers are capped, the air cannot pass into the traps but the inertia of the solids causes the solids to continue in a horizontal direction while the air itself turns upwardly.

In Fig. 8, which is a slightly modified form of the device, the parts are identical with that previously described except that a screen 96 covers the lowermost plate 10-A and the plate 28-A discharges directly upon the screen 96 which is spaced from the plate 10-A at its outer edge by means of the ring 29-A.

In this form of the device, the ring 29-A

is provided with radial slots 33-A through which air from under the plate 28-A is directed radially toward the center of the device thereby discouraging any of the particles from coming to rest between the openings 69-A.

Above the lowermost end of the plate 28-A is disposed the circular ring 97 whose lower edge 98 is held above the plate 28-A by means of the dowel pins 99. The operation of this form 10 of the device is very similar to that previously described.

As shown in Fig. 7, all of the material is kept in a continuous state of agitation until the concentrates pass downwardly into the bleeder pipe 15 20 or the gangue is displaced by the incoming material and the air flotation.

The member 31 projects through the inclined plate 100 which serves to discharge the waste materials from the machine.

20 The sides 101 and 102 extend above the top of the screen 38. The members 103, 104, and 102 are supported by the members 78 and 80.

I claim:

1. In a concentrator, the combination of a 25 perforated plate whose top surface slopes downwardly toward a central point, a bleeder pipe adapted to draw materials from said central point, an air pipe within said bleeder pipe having a perforated, upwardly discharging air nozzle thereon constituting a cover for the upper end of said bleeder pipe and spaced from the inlet of the bleeder pipe and affording a passageway thereto around the rim thereof, means for causing air to pass upwardly through said perforated 30 plate and a screen over said perforated plate adapted to remove from the materials deposited on said plate the oversized materials which are discharged as gangue.

2. A concentrator of the class described having 40 in combination a plurality of concentric compartments having perforated plates across the upper end thereof, the top side of said plates sloping downwardly toward the center of the innermost compartment, means for delivering air 45 to each of said compartments for the purpose of agitating the materials above same, the innermost compartment having an air supply pipe therein provided with an upwardly discharging air nozzle at its upper end forming an elevated 50 cover for the uppermost end of the innermost compartment, which innermost compartment serves as a bleeder pipe, a dust trap formed at the lower end of each of said compartments from 55 which dust may be withdrawn, and means for withdrawing concentrates from the lower end of said bleeder pipe.

3. A concentrator of the class described having 60 in combination a perforated screen having its top side sloping downwardly toward the center thereof and having an outlet opening at the lowermost central point, a plurality of compartments formed under said screen through which governed quantities of air may be delivered upwardly through the various screen portions above 65 their respective compartments, a bleeder pipe on the under side of said screen communicating with said central opening and an air spraying head mounted over said opening and having its edges spaced from said screen, and a coarse 70 screen over said first mentioned screen sloping downwardly to the rim of said air spraying head and spaced above said first mentioned screen.

LYLE MCLEAN.
